UNITED STATES PATENT OFFICE.

EDWARD C. RUTTENBERG, OF CHICAGO, ILLINOIS.

LAMP.

Application filed December 8, 1922. Serial No. 605,650.

To all whom it may concern:

Be it known that I, EDWARD C. RUTTENBERG, a citizen of the United States, residing at Chicago, in the county of Cook and State of Illinois, have invented new and useful Improvements in Lamps, of which the following is a specification.

This invention relates to lamps, and more particularly to distinctive artistic lamps which embody in the pedestal construction pottery vases or the like, and an object of the invention is to provide means for securely holding the vase in place, and for bracing the vase, the said bracing structure being artistically arranged to add to the attractiveness of the appearance of the vase.

Other objects of the invention will appear in the following detailed description taken in connection with the accompanying drawings wherein:

Fig. 1 is a side elevation of a lamp constructed in accordance with this invention.

Fig. 2 is a vertical section taken on the line 2—2 of Fig. 1 with the shade removed.

Fig. 3 is a horizontal section taken on the line 2—2 of Fig. 1.

Fig. 4 is a vertical section through a modified form of the lamp illustrating the manner of embodying a pottery vase in a floor lamp pedestal.

Figs. 5, 6 and 7 are side elevations of modified forms of the lamp structure.

Fig. 8 is a cross section on the line 8—8 of Fig. 7.

Referring more particularly to the drawings, the improved lamp structure comprises the vase 1 which may be of any desired shape, construction or finish. The base 2 of the vase 1 is drilled to provide an opening 3 which aligns with the mouth of the vase and a standard preferably in the form of a pipe 4 extends longitudinally through the vase, extending through the opening 3 in the bottom 2 and upwardly through the mouth of the vase. The pipe 4 may have any approved type of head 5 such as used in lamps, mounted thereon and it also may be extended or constructed so as to provide the usual form of shade attachment, and clamp or finial as shown at 6. The pipe 4 is hollow so as to permit the electric conducting wires to be passed upwardly therethrough. The pipe 4 provides a plate 7 carried by the base structure 8 of the lamp and the lower end of the pipe is threaded and has a nut 9 threaded thereon. A mushroom 10 is

mounted upon the pipe and engages the upper end or mouth of the vase 1. A tube 11 is mounted upon the pipe 4 and it extends through the base 2 and engages the plate 7 at its lower end, while the upper end of the tube 11 engages against the under surfaces of the central portion 12 of the mushroom 10 so that as the nut 9 is tightened on the pipe 4 for securely clamping the various parts in place the pressure provided by the tightening of the nut will draw the mushroom 10 downwardly against the end of the tube 11 while the pressure at the bottom of the base will also be against the lower end of the tube 11 thereby relieving the vase 1 of any pressure which would tend to break it.

Ornaments 14 constituting a vase guard are attached to the base 8 in any suitable manner such as soldering and these ornaments, in Figs. 1 to 3 of the drawings comprise metal leaves or flowers. The leaves 14 extend upwardly along the vase 1 and it will be noted by particular reference to Fig. 3 of the drawings that these metal leaves hug or fit tightly against the outer surface of the vase at spaced points serving the dual function of bracing the vase as well as ornamenting it in the lamp construction.

In Fig. 4 of the drawings a floor lamp structure is shown which comprises the pedestal 20 upon the lower end of which a base 21 is provided. The pedestal 20 comprises in this construction a standard preferably in the form of a pipe 22 which corresponds with the pipe 4, a tube 23 which encloses the pipe and the main tubular body 24 which rests on the base and encloses the tube 23. The base 21 is provided with an opening 25 through which the pipe 22 extends and the lower end of the pipe 22 is threaded and has a nut 26 mounted thereon to permit the clamping of the mushroom 27 tightly in place about the mouth of the vase 28 which is embodied in the lamp pedestal structure. The tubular body 24 of the lamp pedestal 20 has a saddle or socket member 29 at its upper end which corresponds to the base 8 in that the base of the vase 28 rests there against. Leaves or a husk as shown at 30 is formed upon the member 29 to constitute a vase guard and extends upwardly about the exterior of the base of the vase 28 adjacent its base for serving the dual function of ornamenting

the lamp structure and bracing the vase exteriorly.

In Fig. 5 of the drawings a slight modification of the invention is shown in which the plate 40 upon which the vase 41 rests is elevated from the base 42 being supported above the base 42 by a standard preferably in the form of a tubular or pipe like construction 43 and the legs 44, which legs are constructed of iron and ornamented to add to the attractiveness of the design or appearance of the lamp. Metal leaves or analogous decorating members 45 are formed integrally with the legs 44 and extend upwardly therefrom, to constitute a guard embracing the exterior of the vase 41 adjacent its lower portion.

In Fig. 6 of the drawings, the vase 50 is embraced and ornamented by a guard in the form of metal stem or vine 51 which extends spirally about the vase and has leaves and flowers thereon to add to the attractiveness of the design. The stem 51 may be soldered or otherwise suitably attached to the base 52.

Figs 7 and 8 show a further modified form of the invention in which the supporting plate 60 is supported about the base structure 61 in the same manner in which the plate 40 is supported. The base 61, however, is in turn supported above the structure upon which the lamp will rest by the metal legs 62, which legs are turned in as shown at 63 to provide the necessary supporting surfaces or shoulders for the plate 60. Arms 64, which constitute a vase guard, are formed of metal and integral with the legs 62 and rise from the legs, embracing the vase 66 at spaced points about its outer surface. It is to be understood that the arms 64 may be decorated or constructed in any desired artistic manner so as to add to the appearance of the lamp structure. The arms 64 are connected one to another short distances below their upper ends by a vase encircling band 67 which tightly hugs the vase and cooperates with the arms 64 in bracing it and preventing liability of breakage during handling or shipment of the lamp structure.

From the foregoing description taken in connection with the accompanying drawings

it will be apparent, that wherein the several modified forms of the lamp structures the combination of the metal ornaments or decorating means with the pottery vase is carried out and that the said metal ornaments are arranged not only to ornament or add to the artistic value of the lamp but also to brace and protect the pottery vase.

It is, of course, to be understood that the invention may be constructed in other manners and the parts associated in different relations and, therefore, I do not desire to be limited in any manner except as set forth in the claims hereunto appended.

Having thus described my invention what I claim is:

1. In a lamp, a pottery vase, a base including a plate upon which the vase rests, a pipe projecting centrally through the vase and extending through said plate, a mushroom on said pipe and engaging the top of the vase, a nut threaded on the pipe and engaging the under surfaces of said plate for clamping the plate and mushroom tightly against the base and mouth of the vase respectively, and a tube on said pipe and engaging said plate and mushroom to prevent crushing of the vase.

2. In a lamp, a pottery vase, a base including a plate upon which the vase rests, a pipe projecting centrally through the vase and extending through said plate, a mushroom on said pipe and engaging the top of the vase, a nut threaded on the pipe and engaging the under surfaces of said plate for clamping the plate and mushroom tightly against the base and mouth of the vase respectively, and a tube on said pipe and engaging said plate and mushroom to prevent crushing of the vase, and metal ornaments carried by said base and extending upwardly about and embracing the exterior of the vase.

3. The combination in a lamp structure, of a base, a standard connected to and rising from the base and adapted to carry a lamp head, a vase surrounding the standard, and an artistic guard supported on the base and receiving the vase.

In testimony whereof I affix my signature.

EDWARD C. RUTTENBERG.
